UNITED STATES PATENT OFFICE.

CARDEN L. GREEN AND WILLIAM W. HINES, OF TULSA, OKLAHOMA, ASSIGNORS OF ONE-THIRD TO W. G. JOHNSON, OF BROKEN ARROW, OKLAHOMA.

BAILER.

Application filed March 22, 1923. Serial No. 626,981.

To all whom it may concern:

Be it known that we, CARDEN L. GREEN and WILLIAM W. HINES, citizens of the United States, and residents of Tulsa, in the 5 county of Tulsa and State of Oklahoma, have invented certain new and useful Improvements in Bailers, of which the following is a specification.

In the drilling of an oil or gas well, it is 10 frequently necessary to introduce water into the bottom of the hole because the hole is dry and the water is used for the purpose of mixing or fluxing with the cuttings so that the drill bits will more efficiently cut the 15 formation and so that the cuttings may be efficiently introduced into the bailer and subsequently withdrawn from the hole.

Frequently when a bailer full of water is introduced into the well it will encounter 20 soft earth or mud and the dart of the bailer will sink into the soft earth or mud and consequently the valve of the bailer will remain seated. When the valve is thus allowed to remain seated water contained in the bailer 25 is not discharged and the drilling operation is greatly retarded.

Therefore, an important object of this invention is to provide a bailer having means whereby the valve may be positively unseated when the bailer loaded with water reaches 30 the bottom of the well so that the water may be efficiently discharged.

A further object of the invention is to provide a bailer having a valve operating 35 means which will not in any way interfere with the use of the bailer for withdrawing cuttings and the like from the well.

A further object is to provide a bailer 40 which is of highly simplified construction, simple in use and cheap to manufacture.

Other objects and advantages will be apparent during the course of the following description.

In the accompanying drawing forming a 45 part of this application and in which like numerals are employed to designate like parts throughout the same,

Figure 1 is a vertical sectional view 50 through the improved bailer, the parts being shown in the position they occupy when the device is used for withdrawing cuttings and the like from the well.

Figure 2 is a vertical section through the 55 bailer, the same being shown in the water discharging position.

Figure 3 is a detail elevation illustrating a pair of jars which may be employed in connection with the invention.

In the drawing wherein for the purpose of illustration is shown a preferred embodiment of the invention the numeral 5 designates a tubular body of a bailer, which body is provided at its forward end with the usual annular valve seat 6. The valve seat 6 is engaged by a semi-spherical valve 7 having a stem 8 to which a contact plate or member 9 is connected. As in the case of the bailers now in use the engagement of the contact member 9 with the bottom of the well unseats the valve 7 so that the cuttings and the like may freely enter the tubular body 5 for subsequent withdrawal from the well. Of course when the valve is unseated as illustrated in Figure 2 the forward end of the bailer rests upon the shoulders 10.

In carrying out the invention the rear portion of the tubular body 5 is provided with a yoke 12 through which a plunger or rod 14 is extended. Figure 1 illustrates that the rear portion of the plunger or rod 14 is enlarged as indicated at 15 and is provided with an opening 16 for the reception of the lower end of a line or lowering means 17. The enlarged end or head 15 provides a convenient means whereby a fishing tool may be engaged with the bailer in case the line 17 is broken.

In the use of the device for withdrawing material from the well the plunger is connected to a cross member 20 by means of a pin 21 and a latch 22. The latch 22 is extended through a slot 24 in the plunger 14 and as the plunger 14 has connection with the lowering line 17 the weight of the bailer will be borne by the latch 22 and the latch will be engaged with the bottom of the slot 24. The pin 21 cooperates with the latch 22 in holding the plunger 14 against longitudinal movement in the bailer when the device is used for withdrawing cuttings or the like from a well.

When it is desired to dump a quantity of water in the bottom of the well the bailer is arranged several feet above the top of the hole and the pin 21 is detached. The water loaded bailer is now introduced into the well and when the contact member 9 settles in the mud in the bottom of the well the tubular body will come to a rest and the line 17 will be loosened somewhat whereby the plunger 110

14 may descend slightly. When the plunger 14 thus descends the top wall of the slot 24 will swing the latch on its pivot 22 and thereby release the latch from engagement 5 with the plunger. The plunger or rod 14 may now be elevated thru the line 17 and the chain or other flexible element 30 connecting the rod 14 to the valve 7 will positively unseat the valve 7. It is quite obvious that the 10 positive unseating of the valve 7 will permit the water contained in the bailer to be quickly discharged into the bottom of the well. When the water contained in the bailer has thus been discharged the bailer is 15 withdrawn and when a sufficient quantity of water has been introduced into the well the latch 22 and the pin 21 are again connected to the rod 14 so as to hold the rod against longitudinal movement with relation 20 to the tubular body.

A slightly modified form of invention is illustrated in Figure 3 wherein it shows that the rod 40 may be provided at its forward end with a loop or jar 42 with which 25 a second jaw or loop 43 is interlocked. The forward portion of the jaw 43 is connected to a rigid link 46 which is in turn connected to the rear end of the valve through the medium of an attaching loop 48. In this 30 case also the rod 40 may be detachably connected to the tubular body and held against movement with relation to the same and of course the rod is caused to support the weight of the bailer through the medium of 35 the latch 22. Of course in carrying out this form of the invention the jars will be so proportioned that sufficient slack is provided to allow the rod to be positively disconnected from the latch when the rod is 40 released.

With reference to the foregoing description taken in connection with the accompanying drawing it will be seen that a bailer constructed in accordance with this invention 45 is provided with simple and reliable means whereby the water may be reliably discharged at the bottom of the well and during the ordinary use of the bailer the rod 14 and associated elements do not in 50 any way interfere with the filling of the bailer or the subsequent withdrawal of the same.

Having thus described the invention, what is claimed is:—

55 1. A bailer for use in wells comprising a tubular body, a valve seat carried by the body, a valve associated with said valve seat and having a dart, a rod extending into the tubular body and having a limited sliding connection with the valve, and a latch connecting the body to the rod, said rod having its upper portion provided with means adapting the same for connection with the lowering lines of the bailer.

60 2. A bailer for wells comprising a tubular

body adapted for the reception of water and having its forward end provided with a valve seat, a valve associated with the valve seat and having a dart, a rod slidable into the tubular body, means flexibly connecting the rod to the valve for unseating the valve when the rod is moved rearwardly, said rod being provided with a slot, and a latch pivoted to the body and received in said slot, said rod constituting a bailer supporting means and adapted for connection with a lowering member. 75

3. A bailer for wells comprising a body adapted for the reception of water and provided with a valve seat, a valve associated with the valve seat, a rod slidable into the tubular body, means flexibly connecting the rod to the valve for unseating the valve when the rod is moved rearwardly, said rod being provided with a slot, a latch pivoted to the body and received in said slot, and a pin cooperating with the latch in holding the rod against longitudinal movement with relation to the body. 80

4. A bailer for wells comprising a tubular body having its forward end provided with a valve seat and its rear end provided with a yoke, a rod slidable through said yoke and having a slot, a latch pivoted to said yoke and received in said slot whereby the weight of the bailer is transmitted to the rod, a valve associated with said valve seat, and means providing a loose-jointed connection between the rod and the valve. 85

5. A bailer for wells comprising a tubular body having its forward end provided with a valve seat and its rear end provided with a yoke, a rod slidable through said yoke and having a slot, a latch pivoted to said yoke and received in said slot whereby the weight of the bailer is transmitted to the rod, a valve associated with said valve seat, means providing a loose-jointed connection between the rod and the valve, and a pin extending through said rod and cooperating with the latch in holding the rod against longitudinal movement with relation to the tubular body. 100

6. A bailer for wells comprising a body having a valve seat and a yoke, a rod slidable through said yoke and having a slot, a latch pivoted to said yoke and received in said slot whereby the weight of the bailer is transmitted to the rod, a valve associated with said valve seat, means providing a loose-jointed connection between the rod and the valve, the rear portion of the rod being provided with a head by means of which the rod may be connected to a lowering line. 110

7. A bailer comprising a tubular body having a yoke, a cross piece carried by the yoke, a rod slidable through the cross piece and having a slot, a latch pivoted to the cross piece and received in said slot, a pin 120

- extending through said rod adjacent said cross piece and cooperating with said latch in holding the rod against extensive longitudinal movement with relation to the tubular body, a valve seat carried by the forward end of the tubular body, a valve cooperating with said valve seat, and a chain providing a connection between the valve and the rod.
10. 8. A bailer for wells comprising a body, a valve carried by the body, a bailer supporting rod having a loose jointed connection with said valve, and a latch connecting the rod to the body, said bailer supporting rod having its upper portion provided with means adapting the same for connection with the lowering lines of the bailer.
9. A device of the character described comprising an elongated receptacle provided at its top with a bail having a hole, and having its bottom formed with an opening, a valve member including a head and a dart connected by a neck portion slidable through said opening, said head being with- 25 in the receptacle and the dart being there- below, a plunger slidable through the hole in the bail and provided with suspension means and a slot, a connection between said plunger and said valve member, and a trigger operable within said slot and disposable transversely of the plunger to engage and support the receptacle.
10. A device of the character described comprising an elongated receptacle provided at its top with a bail having a hole, and having its bottom formed with an opening, the valve member including a head and a dart connected by a neck portion slidable through said opening, said head being with- 35 in the receptacle and the dart being there- below, a plunger slidable through the hole in the bail and provided with suspension means and a slot, a connection between said plunger and said valve member, and a trigger operable within said slot and disposable transversely of the plunger to engage and support the receptacle, the trigger consisting of an elongated bar pivoted at a point spaced from its center whereby the trigger will naturally tend to depend in vertical 50 position, said dart being engageable with the bottom of the receptacle to prevent being drawn through the opening therein.
11. A device of the character described comprising an elongated receptacle having its top open and provided with a bail having a hole therein, the bottom of the receptacle being formed with an opening, a valve member above said opening having a neck portion slidable therethrough, a plunger 55 slidable through the hole in the bail and equipped with suspension means, a flexible member connected with the plunger and said valve member, said plunger being formed with a slot, and a trigger pivoted eccentrically and capable selectively of extending transversely in engagement with the lower side of the bail to prevent upward movement of the plunger with respect to the bail or being disengageable from the 60 bail to permit the plunger to move upwardly relatively thereto.
12. In a device of the character described, a receptacle having an open top and having its bottom formed with a valve seat, a valve 75 co-operating with said seat and having an extension projecting therethrough, a support at the top of the receptacle, a plunger slidable through said support and equipped with suspension means, a trigger co-operating with the support and with the plunger for holding the plunger against upward movement, and a flexible connection between the plunger and the valve.
13. In a device of the character described, an open topped receptacle provided in its bottom with a valve seat, a valve within the receptacle co-operating with said seat and having an extension projecting beyond the seat, a support at the top of the receptacle, 80 a plunger slidable through the support and flexibly connected with the valve, and a trigger for normally preventing upward sliding movement of the plunger, and means whereby the trigger will be released upon 85 downward movement of the plunger.
